UNITED STATES PATENT OFFICE.

LOUIS S. HENDERSON, OF PHILADELPHIA, PENNSYLVANIA.

DESIGN FOR A RUG OR SIMILAR ARTICLE.

Application filed May 5, 1928. Serial No. 26,579. Term of patent 3½ years.

To all whom it may concern:

Be it known that I, LOUIS S. HENDERSON, a citizen of the United States, residing in the city and county of Philadelphia, State of Pennsylvania, have invented a new, original, and ornamental Design for a Rug or Similar Article, of which the following is a specification, reference being had to the accompanying drawing, forming part thereof.

The figure is a plan view of a rug or similar article showing my new design. The design illustrated constitutes exactly one-half of the rug or similar article, and the other half consisting of an exact duplication of the design shown in the drawing.

I claim:—

The ornamental design for a rug or similar article, as shown and described.

LOUIS S. HENDERSON.
